METHOD OF GRINDING VALVE SEATS AND
SIMILAR AREASRobert S. Beverlin, Toledo, Ohio, assignor to The
Hall Manufacturing Company, Toledo, Ohio, a
corporation of Ohio

Application April 17, 1944, Serial No. 531,391

6 Claims. (Cl. 51—241)

This invention relates primarily to the art of grinding valve seats of internal combustion engines, particularly those of the type having closed cylinder heads with the valve seats in such heads, as in radial aircraft engines, thus requiring access thereto for grinding purposes to be had through the open inner end of the cylinder.

In the grinding of valve seats in such a cylinder, the grinding tool is disposed within the closed cylinder head end thereof where it is difficult of access for the purpose of applying thereto the necessary grinding pressure, and the cylinder bore is usually of such small diameter that the tool must be small so that its weight is not sufficient to impart the desired grinding pressure against the valve seat. If the grinding pressure is less than that normally required, the efficiency of the grinding operation is gradually reduced, both in time and results, and this is increased if the plane of the valve seat is inclined to the cylinder axis.

Furthermore, in the grinding of such valve seats, a liquid coolant is introduced interiorly of the cylinder and flows down to and in engagement with the edge of the grinding wheel. The high speed of the wheel causes this coolant to flow to and be thrown from the peripheral edge of the wheel by centrifugal action so that very little if any of the coolant will reach the grinding surface, thereby resulting in a hot grinding operation.

An object of the invention is the provision of a simple, efficient and novel method and means for acting on the grinding wheel of a valve seat grinding tool through the valve seat passage to apply a predetermined grinding pressure thereto.

Another object of the invention is to utilize pneumatic suction through the valve seat passage of an internal combustion engine cylinder to act on a grinding tool for the valve seat of such passage to hold it to the seat with a predetermined pressure to effect the desired grinding operation.

Another object of the invention is the provision of a simple and efficient method, of pneumatic character, operable through the valve seat opening of a cylinder of the class described to not only act to hold a grinding wheel in seat grinding position under a predetermined pressure, but also to prevent a coolant supplied to the wheel from being drawn away from its seat grinding surface by centrifugal action.

Other objects and advantages of the invention will be apparent from the following description and from the accompanying drawing.

The drawing is a central longitudinal section 55 may be, is connected up to a vacuum source

of a cylinder, with a part in full and with a valve seat grinding tool in operative position therein, together with means attached thereto for practicing the feature of the invention.

5 Referring to the drawing, 1 designates a cylinder of a radial type aircraft engine, with the head or closed end thereof provided with two passages 2 one of which forms the inlet passage and the other the exhaust passage for the cylinder and each having at its inner end the customary valve seat 3. In each passage 2, in axially aligned relation to the valve seat opening, is a valve stem guide opening 4 adapted to receive and guide the movements of the associated valve 10 stem (not shown). When the valve is removed from the cylinder head, the guide opening 4 receives and centers a pilot stem 5, one end of which projects through the valve seat opening and into the cylinder to form a mount and guide 15 for a valve seat grinding tool 6, as well understood in the art. The tool 6 is preferably but not necessarily of the eccentric type wherein the center of rotation of the grinding wheel 7 is slightly offset relative to the longitudinal center 20 of the pilot stem 5, so as to cause the wheel, as it is rapidly rotated about its axis and more slowly turned about the axis of the pilot stem, to have a high speed grinding action only at one side of its axis against the valve seat and a slow speed 25 progression around the valve seat of the grinding point. The tool is necessarily small and of light construction due to its use in cylinders having small diameter bores. Nothing novel is claimed for the tool itself and it therefore need not be 30 more specifically described.

35 A liquid coolant, in the present instance, is supplied to the surface being ground from a hose or tube 8 which receives its supply of coolant from any suitable source and has its discharge 40 end terminating within the cylinder adjacent to one side so that the coolant will flow down the inner side wall of the cylinder to the valve seat 3 being ground.

45 During the grinding of a valve seat the smallness and consequent lightness of the tool 6 prevents it from exerting by gravity action the necessary pressure of its grinding wheel 7 against the valve seat 3 to effect a rapid and efficient grinding operation, and due to the small diameter 50 of the cylinder bore it is difficult to apply any manual pressure to the tool for the purpose. In order to compensate for this lack of grinding pressure, the outer end of the passage 2 leading to or from the valve seat opening, as the case

whereby a suction action is applied through such passage and acts against the grinding wheel 7 to hold it to the valve seat under a predetermined pressure, which is determined by the suction pressure. This method of applying grinding pressure to the grinding wheel is not only efficient in obtaining the desired grinding action of the wheel on the valve seat, but also in drawing the coolant to the valve seat and coacting grinding surface of the wheel to have the desired cooling action thereon rather than being carried to the extreme peripheral surface of the wheel away from the valve seat and thrown therefrom by centrifugal action. This in itself is an important feature.

In the illustrated embodiment of the invention, 10 designates a tank for a liquid coolant and into which the open end of a suction pipe 11 is submerged. This pipe connects with a suitable suction source indicated diagrammatically at 12, and between this source and the tank 10 the pipe has a side connection at 13 with the outer end of the passage 2, the valve seat of which is to be ground. The connection 13 is adapted to seat against the outer marginal edge wall of the passage 2 and to be secured thereto by screws, or in any other suitable manner. The vacuum pressure may be determined by the height of the coolant column in the lower end of the pipe 11 and in practice it is found that from sixteen to twenty inches raise of liquid in the pipe is sufficient. The top of such column, however, should be below the connection 13, so that the coolant which enters the passage 2 may flow outward therefrom through the connection 13 and pipe 11 to the tank 10. In the present instance, the coolant supply tube 8 leads from the tank 10 and has a pump 15 interposed therein.

While, in the use of an eccentric type of grinding tool, as illustrated, a clearance space is present between the seat and grinding wheel due to the eccentric seating action, this clearance is customarily about twenty-one thousandths of an inch at its widest point and therefore is not sufficient to seriously interfere with the desired suction action on the wheel. The presence of such clearance also facilitates the drainage movement of the coolant over and through the seat by the suction action.

While the invention has been particularly described for use in connection with the grinding of valve seats disposed interiorly of engine cylinders, it is not desired to restrict it to such use, as it may be used to advantage in the grinding of any area which is circular or substantially circular and has a passage leading inwardly therefrom, whereby suction within the passage at the inner side of the grinding tool will permit atmospheric pressure, acting on the tool at its outer side, to hold it to the seat or area being ground.

I wish it understood that my invention is not limited to any specific construction, arrangement or form of the parts, as it is capable of numerous modifications and changes without departing from the spirit of the claims.

Having thus described my invention, what I claim as new and desire to secure by United States Letters Patent, is:

1. The method of holding a valve seat facing

tool in operative coaction with a valve seat at the cylinder end of a passage having communication with a cylinder, which consists in creating a vacuum within the passage whereby atmospheric pressure at the cylinder side of the tool acts on the tool to hold it under predetermined pressure in facing coaction with the valve seat.

2. The method of holding the grinding wheel of a valve seat facing tool in predetermined 10 grinding coaction with a valve seat at the cylinder end of a passage which is in communication with the cylinder of an internal combustion engine and wherein the wheel closes or substantially closes the passage, which consists in applying a predetermined pneumatic force on the wheel through said passage to hold it in predetermined grinding coaction with said seat.

3. In the art of grinding the valve seats of the cylinders of internal combustion engines 20 wherein the rotatable grinding wheel of a valve seat facing tool has grinding engagement with a valve seat internally of the cylinder and wherein a liquid coolant is supplied to the wheel, the method of preventing such liquid from being thrown away from the seat grinding portion of the wheel by centrifugal action, which consists in causing a pneumatic force to act through the cylinder and around the grinding wheel to counteract the said centrifugal force and cause the coolant to partially at least flow outwardly from the cylinder over the valve seat.

4. In the art of grinding the valve seats of cylinders of internal combustion engines wherein the rotatable grinding wheel of a valve seat facing tool has grinding engagement with a valve seat internally of the cylinder and wherein a coolant is supplied to the wheel and seat, the method of holding the wheel to the seat with predetermined grinding force and also preventing the coolant from being thrown from the seat by centrifugal action due to the rotation of the wheel during grinding, which consists in applying a predetermined suction on the wheel away from the cylinder and through the passage leading from within the valve seat.

5. The method of holding a grinding tool to an area to be ground and wherein a space is provided within such area and is open thereto, which consists in creating a vacuum within said space, whereby atmospheric pressure at the outer side of the tool with respect to said space acts on the tool to hold it under predetermined pressure in facing coaction with said area.

6. The art of grinding substantially circular areas bounding an open passage leading inwardly through said area wherein a rotatable grinding tool has grinding coaction with the area in substantially closing relation to said passage and wherein a coolant is supplied to the wheel and area, the method of holding the wheel to said area with predetermined grinding force and also preventing the coolant from being thrown from the area by centrifugal action due to the rotation of the wheel during grinding, which consists in applying a predetermined suction in said passage and to the side of the wheel exposed to the passage.

ROBERT S. BEVERLIN.
